(57) CLAIM

The ornamental design for a open-toe shoe, as shown and described.

DESCRIPTION

FIG. 1 is a top plain view of an open-toe shoe shown in accordance with my new design;

FIG. 2 is a bottom plain view thereof,

FIG. 3 is an outside elevational view thereof,

FIG. 4 is an inner (arch) side elevational view thereof,

FIG. 5 is a front end elevational view thereof; and,

FIG. 6 is a back end elevational view thereof.

The figures shown are of a left shoe, the right shoe being a mirror image thereof.
